UNITED STATES PATENT OFFICE.

WARREN HARRIS BRIGHT, OF WELLSTON, OHIO.

HEATING SYSTEM.

No. 863,504.

Specification of Letters Patent.

Patented Aug. 13, 1907.

Application filed September 14, 1906. Serial No. 334,653.

To all whom it may concern:

Be it known that I, WARREN HARRIS BRIGHT, a citizen of the United States, residing at Wellston, in the county of Jackson and State of Ohio, have invented a new and useful Heating System, of which the following is a specification.

This invention relates generally to heating systems and particularly to an improved form of hot water receptacle and heater.

10 The object of the invention is to economize on fuel and heat.

With the foregoing and other objects in view, which will appear as the description proceeds, the invention resides in the combination and arrangement of parts 15 and in the details of construction hereinafter described and claimed, it being understood that changes in the precise embodiment of invention herein disclosed can be made within the scope of the following claims without departing from the spirit of the invention or sacrificing any of its advantages.

In the accompanying drawings forming part of this specification:—the figure is a vertical central section through a device constructed in accordance with the invention.

25 Like reference numerals indicate corresponding parts in the different figures of the drawings.

The reference letter A indicates a hot water receptacle or reservoir; the letter B indicates a heater, which may be of any suitable form and construction; and C, a 30 gas jet or other suitable source of heat.

Extending through the upper end 1 of the receptacle A is an inlet pipe 2 for cold water. The inlet pipe 2 extends down through the interior of the receptacle A and the lower end 3 thereof terminates a short distance 35 above the bottom 4 of the receptacle which, in the embodiment of invention illustrated, is concaved as shown, although it is to be understood that any other style of receptacle or boiler A can be employed.

Threaded through an opening in the bottom 4 of the 40 receptacle A is a pipe 5 leading from the heater B, both ends of which pipe are open. Into the upper end of the pipe 5 is screwed a pipe 6 reaching to the top of the receptacle A for conveying thereto water from the heater B. The lower end of the pipe 5 extends through the 45 heater from its top nearly to its bottom for the discharge of cold water thereinto. A central longitudinal partition 7 extends across the pipe 5 from near the upper end to near the lower end, dividing the mid-portion of the pipe into two channels 8 and 9, the channel 8 being 50 closed at its upper end by a wall 10 extending from the partition 7 to one side of the pipe, while the channel 9 is closed at its lower end by a similar wall 11. An inlet passage 12 is made in the side of the divided pipe 5 just below the wall 10 through which cold water from the 55 bottom of the receptacle passes into the channel 8 and thence through the lower end of the pipe into the heater.

A similar passage 13 is formed in the pipe 5 above the wall 11 and near the top of the heater for the exit of hot water from said heater into the channel 9 and thence through the upper end of said pipe 5 and the pipe 6 to 60 the top of the receptacle, from whence it can be drawn off in the usual manner.

The peculiar advantage of the present invention, by which it effects an economy of fuel and heat, is that after the receptacle A has been filled with water from 65 the inlet pipe 2, and the burner C has been started, the cold water emerging from the lower end of the pipe 2 passes through the passage 8 into the heater B from which it is conducted directly by the pipe 6 to the upper portion of the receptacle A without being permitted 70 to mix with the water of lower temperature in the lower end of the receptacle A. It will be understood that as the hot water constantly passes up through the pipe 6 in the center of the receptacle A, it will serve gradually 75 to raise the temperature of the body of water in the receptacle A above the lower end of the inlet pipe 2. This gradual raising of the temperature of the water in the upper end of the receptacle A causes it to remain in its raised position so that the cold water entering 80 through the inlet pipe 2 does not rise into the upper end of the receptacle A but continues directly to the passage 8 and is immediately heated and carried off. By employing a receptacle A having a concaved bottom, any heat which passes around the heater B will impinge 85 against the lower end of the receptacle A and will serve to heat the same.

It will be understood that the improvements of the present invention can be used in connection with boilers and heaters of many different forms.

The construction described constitutes an extremely 90 strong, simple, durable, inexpensive and thoroughly efficient heating arrangement.

What is claimed is:—

1. In a hot water heater, the combination of a water receptacle, a heater and a single pipe directly connecting said parts, said pipe having a central partition dividing its mid-portion only into two channels closed at opposite ends and also having a passage leading into each of said channels from the side of said pipe near the closed end of the channel. 95

2. In a hot water heater the combination of a water receptacle, a heater below the same, and a pipe directly connecting said parts, said pipe having a central longitudinal partition, connected at each end by a wall to the side of the tube to form two channels each of which channels is 100 closed at one end and opens at the other end into the adjacent end of the tube, passages being formed in opposite sides of the tube into the closed ends of the channels.

In testimony that I claim the foregoing as my own, I have hereto affixed my signature in the presence of two 110 witnesses.

WARREN HARRIS BRIGHT.
